(57) **CLAIM**

The ornamental design of an adjustable sensor clip, as shown and described.

DESCRIPTION

FIG. 1 depicts a top perspective view of a sensor clip; FIG. 2 depicts a bottom perspective view of the sensor clip; FIG. 3 depicts a front view of the sensor clip; FIG. 4 depicts a back view of the sensor clip; FIG. 5 depicts a left view of the sensor clip; FIG. 6 depicts a right view of the sensor clip; FIG. 7 depicts a top view of the sensor clip; FIG. 8 depicts a bottom view of the sensor clip; FIG. 9 depicts a top perspective view of the sensor clip in an extended position; FIG. 10 depicts a bottom perspective view of the sensor clip in an extended position; FIG. 11 depicts a front view of the sensor clip in an extended position; FIG. 12 depicts a back view of the sensor clip in an extended position; FIG. 13 depicts a left view of the sensor clip in an extended position; FIG. 14 depicts a right view of the sensor clip in an extended position; FIG. 15 depicts a top view of the sensor clip in an extended position; FIG. 16 depicts a bottom view of the sensor clip in an extended position; and, FIG. 17 depicts the sensor clip coupled to a device. The broken lines showing parts of the sensor clip are for the purpose of illustrating portions of the sensor clip that form no part of the claimed design. The dash-dot-dash broken lines define the bounds of the claimed design and form no part thereof.
